(57) **CLAIM**

The ornamental design for a fragrance bottle with cap, as shown and described.

DESCRIPTION

FIG. 1 is a perspective view of a fragrance bottle with cap, embodying our new design;

FIG. 2 is a side elevational view thereof, all other side views being identical;

FIG. 3 is a side elevational view thereof with the cover removed;

FIG. 4 is a top view thereof with the cover removed;

FIG. 5 is a perspective view of a second embodiment of a fragrance bottle with cap;

FIG. 6 is a side elevational view thereof, all other side views being identical;

FIG. 7 is a side elevational view thereof with the cover removed; and,

FIG. 8 is a top view thereof with the cover removed.
